DESIGN FOR A STUFFED LOCOMOTIVE TOY

Hazel Nelson Stefany, Maplewood, N. J.

Application November 23, 1945, Serial No. 123,979

Term of patent 14 years

(Cl. D34—15)

To all whom it may concern:

Be it known that I, Hazel Nelson Stefany, a citizen of the United States, residing in Maplewood, county of Essex, and State of New Jersey, have invented a new, original, and ornamental Design for a Stuffed Locomotive Toy, of which the following is a specification; reference being had to the accompanying drawing, forming a part thereof.

Fig. 1 is a side elevational view of a stuffed locomotive toy or similar article embodying my new design.

Fig. 2 is a top plan view thereof taken on line 2—2 of Fig. 1, and

Fig. 3 is a front elevational view thereof taken on line 3—3 of Fig. 1.

I claim:

The ornamental design for a stuffed locomotive toy, as shown.

HAZEL NELSON STEFANY.
